UNITED STATES PATENT OFFICE.

WILLIAM MERZ, OF BERWYN, ILLINOIS, ASSIGNOR, BY MESNE ASSIGNMENTS, TO
WESTERN ELECTRIC COMPANY, INCORPORATED, A CORPORATION OF NEW YORK.

LOADING-COIL FOR TELEPHONE-LINES.

1,184,001.

Specification of Letters Patent. Patented May 23, 1916

Application filed September 15, 1914. Serial No. 861,901.

To all whom it may concern:

Be it known that I, WILLIAM MERZ, a citizen of the United States, residing at Berwyn, in the county of Cook and State 5 of Illinois, have invented certain new and useful Improvements in Loading-Coils for Telephone-Lines, of which the following is a full, clear, concise, and exact description.

This invention relates to loading coils for 10 telephone lines, and its object in general is to improve the efficiency of such coils.

For long distance aerial or underground telephone systems, it is desirable to combine four line conductors in such a manner 15 that two two-wire physical or side circuits form a third or "phantom" circuit. In order to load these circuits according to the Pupin system, each side circuit is equipped with a series of loading coils so 20 wound that they offer to currents in the phantom circuit, as nearly as practicable a non-inductive resistance, and the phantom circuit is equipped with loading coils so wound as to offer to currents in either side 25 circuit, likewise as nearly as practicable, a non-inductive resistance.

It is usual to inclose loading coils in a 30 cast iron case, this material being desirable because cheap, substantial and weather- proof.

The cores of loading coils, to which this 35 invention is applicable, may be of finely stranded iron wire, or of flat laminated iron or otherwise divided, so as to increase their resistance to induced electric forces, and formed into continuous iron rings, or they may be continuous non-magnetic rings. In the core of any such loading coil the eddy 40 current and hysteresis losses, due to small stray fields, are negligible.

According to a known construction and 45 scheme of winding of loading coils for phantom line systems, as described in the Campbell and Shaw Patent No. 980,921, an annular core is provided with inner and outer windings of equal number of turns in a plurality of core sections, preferably two and four sections in the side circuit coil and in the phantom coil, respectively, each line 50 conductor in a coil including serially the inner and the outer windings, respectively, of opposite core sections. With either of such coils, but more especially in the phantom coil, there is some magnetic field external 55 to the coil when opposing currents flow

in the windings of a given core section. This is due to the fact that the outer winding exerts a stronger external magnetizing force than the inner winding. The resultant external magnetic field, due to opposing 60 currents in the two windings, acts in part upon the iron case surrounding the coil, and spends itself to a certain extent in eddy current and hysteresis losses therein, which reacts on the coil and impairs its efficiency. 65 The external field also acts in part on the conductors of the coil itself, unless these conductors are finely stranded, and causes eddy current losses therein.

It is one of the purposes of the invention 70 to minimize these losses. This purpose is effective, for example, in loading coils having continuous iron cores, *i. e.* cores without air-gaps, and is accomplished by giving each inner winding a sufficient number of turns 75 with respect to the outer winding on the same section therewith, so that the magnetizing force of the inner winding is increased and the magnetic field, due to the opposing currents in the two windings, is reduced sub- 80 substantially to a minimum in the regions external to the coil. In other words, this stray magnetic field is virtually driven to the core of the coil, where it can dissipate very little energy instead of being allowed to 85 spend itself in the non-laminated iron of the case and in the outer coil conductors.

The invention will be more fully understood by reference to the accompanying drawings wherein—

Figure 1 is a diagrammatic representation 90 of the core and windings of three loading coils for a phantom telephone line system, including two side circuit coils and one phantom coil; Fig. 2 is a simplified diagram 95 of a typical four-conductor phantom telephone line system, loaded with side and phantom circuit coils; and Figs. 3 and 4 are diagrammatic drawings each showing part of a phantom loading coil in cross- 100 section along the center line of the core, and indicating the distribution of magnetic lines, due to opposing currents in the windings of one quarter section; Fig. 3 indicating the stray field with an ordinary phantom coil, and Fig. 4 the stray field in a coil constructed in accordance with the invention.

Referring first to Fig. 2, the four conductors 1, 2, 3, 4 of a long distance telephone line system are shown connected in a well- 11

known way for phantom working at one end through three repeating coils 5, 6, 7 to three telephone stations 8, 9, 10 and at the other end through three repeating coils 11, 12, 13 to three other stations 14, 15, 16. At proper intervals throughout the length of the line, groups of loading coils are provided, two of such groups 17, 18 being indicated in the diagram, and each group comprising two side circuit loading coils 21 and 22 and one phantom loading coil 23 (or 21^a, 22^a, 23^a).

Each line conductor, for example conductor 1, includes at each group of coils, in series, two sectional windings 24, 25 on a side circuit coil and two sectional windings 26, 27 on a phantom coil. The two sectional windings 26, 27 comprising one line winding element of the phantom coil are, as indicated in Fig. 1, an outer and an inner winding, respectively, of opposite core sections A and C, each covering approximately a quarter core section. For phantom circuit working, the direction of the currents in windings 26 and 27, included in line conductor 1, and likewise in windings 28 and 29, 36 and 37, and 38 and 39, included in line conductors 2, 3 and 4, respectively, is such that the magnetizing forces are cumulative, *i. e.*, all tending to produce a magnetic flux in the same circular direction in the core 31, and the coil offers the required inductance according to the Pupin system of loading. On the other hand, for side circuit working, the currents in these windings tend to produce opposite magnetic forces so that the inductance is very small. However, in this case there will be a resultant stray field occupying the small space 32 (Figs. 3 and 4) between these windings, spreading at or near their ends 33, 34 and returning partly by way of the core 31 and partly by way of the space including the iron case 40 external to the coil. It is this external field of force due to opposing currents in the inner and outer windings that causes the eddy current loss in the case and outer winding conductors. As shown in Fig. 3, when the outer and inner windings have an equal number of turns, the magnetizing force of the outer winding predominates in the space external to the coil, and the greater number of stray magnetic lines, indicated by the curved lines, interlink with the case 40. These external stray magnetic forces can, however, be greatly reduced, in accordance with this invention, by giving to the inner windings a greater number of turns than the outer windings, thus rendering the inner winding, which is nearer the core, the predominant magnetizing force and diverting the greater part of the stray field to the core. The distribution of lines is indicated in Fig. 4. It has been found in certain coils that the magnetic fields, due to opposing

currents in the windings, are reduced substantially to a minimum in the space external to the coil when the inner winding has 10% more turns than the outer winding. The percentage, however, will vary according to the design of the loading coil to which the invention is applied, to the class of service for which the coil is designed, and to the conformation of the inclosing case. The proper ratio in each type of coil can be determined by varying the turns of the inner or the outer winding until the external magnetic forces are substantially reduced to a minimum.

What is claimed is:

1. A loading coil for phantom telephone line systems having an annular core and line windings on a plurality of sections thereof, each line conductor through the coil including windings of opposite core sections, the number of turns in each line conductor being unequally distributed between said opposite core sections. 80

2. A loading coil for phantom telephone line systems having an annular core and inner and outer windings on a plurality of sections thereof, each line conductor through the coil including the inner and the outer windings respectively of opposite core sections, the number of turns in each conductor being unequally distributed between said opposite core sections, whereby the magnetic forces due to opposing currents in said windings are substantially a minimum in the space external to the coil. 90

3. A loading coil for phantom telephone line systems having an annular core and inner and outer windings on a plurality of sections thereof, each line conductor through the coil including the inner and the outer windings respectively of opposite core sections, and the number of turns of an inner winding being greater than the number of the outer winding on the same section, whereby the magnetic forces due to opposing currents in said windings are substantially a minimum in the space external to the coil. 100

4. A loading coil for phantom telephone line systems having an annular core and a plurality of windings in layers on each of a plurality of sections thereof, each line conductor through the coil including windings of opposite core sections located at different distances from the core, the number of turns in each line conductor being unequally distributed between said opposite core sections, whereby the magnetic forces due to opposing currents in said windings are substantially a minimum in the space external to the coil. 110

5. A loading coil for phantom and telephone line systems having an annular core and inner and outer windings on each of four quadrants thereof, each line conductor 120

through the coil including the inner and the outer windings respectively of opposite core quadrants, the number of turns in each line conductor being unequally distributed between said opposite core quadrants, whereby the magnetic forces due to opposing currents in said windings are substantially a minimum in the space external to the coil.

In witness whereof, I hereunto subscribe my name this 8th day of September, A. D. 1914.

WILLIAM MERZ.
